UNITED STATES PATENT OFFICE

JOSEPH HIRSCH VINEBERG, OF OTTAWA, ONTARIO, CANADA

COMBINED GARMENT HANGER AND PACKAGING DEVICE

Application filed July 12, 1929. Serial No. 377,796.

This invention relates to garment hangers. The invention has for its object to provide an improved device which can be readily and inexpensively manufactured, and which can be stacked in blank form and quickly folded to produce a hanger when required.

The invention also provides a device which has means for quickly and easily packaging a garment which has previously been arranged on the hanger.

The device is preferably made from a single sheet of suitable paper, stamped or cut to the required shape and provided with markings or weakened lines to facilitate the folding of device into the desired form.

Further objects of the invention will appear from the following description.

Another object of the invention is to provide a hanger which can be arranged to protect the shoulder portion of a garment from the collection of dust.

The invention consists in the features, construction and arrangements hereinafter described and more particularly pointed out in the appended claims.

Referring now to the accompanying drawings, which illustrate, by way of example, one convenient embodiment of the invention:—

Figure 1 is a front view of a blank constructed according to the invention,

Figure 2 is a perspective view of the device folded for use as a garment hanger,

Figure 3 is a perspective view showing one stage in the folding of the device when it is to be used as a package or wrapper for garments,

Figure 4 is a side elevation showing another arrangement of folding the device for use as a hanger,

Figure 5 is a perspective view of the device when it has been folded to form a package, and

Figure 6 is a fragmentary perspective view of a modified form of the hanger portion of the device.

The invention may conveniently be made from a single piece of stout paper by cutting or stamping the opened or blank form of one suitable arrangement being indicated in Figure 1. The paper is adapted to be folded

about lines of weakness which are indicated by the chain-dotted lines. The illustrated form of the invention comprises a central rectangular area 1 bounded by the weakened lines 2, 3, 4 and 5, and a similar area 6 which is bounded at top and bottom by the line 5 and a fold line 7. Below the area 6 and integral therewith is a rectangular flap portion 8. Rectangular flaps 9 and 10 are integrally connected to the central portion 1 and are adapted to be folded about the lines 2 and 4 respectively.

A relatively narrow, substantially rectangular portion 11 is adapted to fold about the line 3. Laterally projecting portions 12 are integrally connected to a rectangular portion 13 which may be folded about a line 14. If desired, the parts 12 and 13 may be lined with heavier paper as at 12', see Figure 6, to give them greater rigidity as will be readily understood, and the reinforcement may be extended to strengthen the hook 20 as at 20'. The projections 12 can be folded about lines 15, and are preferably provided with inclined slits 16. Connected to the part 13 along a fold line 17 is a rectangular part 18 which is provided with a fold line 19.

A hook-shaped portion 20 is stamped from the paper and arranged so that it remains connected to the device on the line 14. The hook 20 is shown as stamped from the portions 13 and 18, but it will be understood that it might equally well be stamped from the parts 11 and 1.

If desired, a straight fold line 21 may be provided across the parts 9, 1 and 10 for a purpose to be later described and when this line is provided a slit 22 is formed on the line 21 to coact with the hook 20.

To arrange the device as a garment hanger it is folded on the line 14 to bring the parts 12 and 18 against the parts 11 and 1 respectively, and to leave the hook 20 projecting upwardly at the top of the device. The lateral projections 12 are then strengthened by folding the part 18 on the line 19 and inserting the top corners of the part 18 into the slits 16, as indicated in Figure 2. The shoulder portions of a garment may then be placed on the projections 16 and the hook 20 placed

on a rail, peg or other support, and the garment allowed to hang as from any ordinary garment hanger. The garment may be displayed in a store in the manner just described, and when the garment has been purchased it may be packed in the device in the following manner: The portion 18 is disengaged from the slits 16 and flattened against the central portion 1, and the projections 12 are folded inwardly about the lines 15, as indicated in Figure 3. The sleeves or outer parts of the garment are thus folded on to the front of the garment and the hanger portion of the device, with the hook 20, is folded downwardly about the line 3. The lower portion of the garment is then folded within the compass of the central portion 1, after which the flaps 9 and 10 are folded inwardly about the lines 2 and 4, and the portion 6 is folded upwardly about the line 5. The flap 8 is folded over the top of the package into engagement with the other side thereof, as indicated in Figure 5. In this form the package may be secured by any suitable means and carried home by the purchaser or delivered to the purchaser by mail.

A form of locking device and handle is shown in Figure 5. A handle member 23 is secured to the part 1 and a locking member 24 is attached to the part 6. The locking member 24 has a slot 25 which is recessed at 26 to receive the shank part of the member 23. It will be seen that the locking member 24 maintains the handle member 23 against the flap 8 and affords a readily releasable locking device which is sufficiently secure for the purpose for which it is designed.

Figure 4 illustrates another method of folding the device for employment as a hanger. According to this method the device is first folded as shown in Figure 2 and the garment is placed on the projections or lugs 12 as previously described. The parts 1, 6, 9 and 10 are then folded rearwardly and upwardly about the line 3 and the hook 20 is inserted through the slit 22. The parts between the line 21 and the flap 8 are then allowed to fold down about the line 21 and hang in front of the upper part of the garment, as indicated in Figure 4. The device with the garment thereon may then be hung up by means of the hook 20, and the bent parts of the portions 1, 9 and 10 form a cover for the shoulder parts of the garments, which parts are the most susceptible to the collection of dust when the garment is displayed in a store or hung in any other exposed position.

It will thus be seen that the invention provides a combined hanger and wrapper or envelope which is very practical, efficient and inexpensive.

Various modifications within the scope of the appended claims may be made without departing from the invention, it being understood that the foregoing description and ac-

companying drawings are given by way of example only.

I claim:

1. A blank for forming into a combined garment supporting or packaging device comprising a rectangular central area, a similar rectangular area integrally connected with the lower edge of said central area, side flaps carried by the side edges of said central area and a portion having laterally projecting, garment-supporting lugs connected with the upper edge of said central area, a relatively shallow portion of the same width as the central area being connected with the upper edge of said central area, said upper edge being weakened to form a line about which said shallow portion may be folded, the laterally projecting lugs being carried by a substantially rectangular portion connected with the upper edge of said shallow portion. 70 75 80 85

2. A blank as claimed in claim 1, wherein a hook-shaped portion is formed in the portion which carries said lugs.

3. In a garment-hanging device a rectangular portion having laterally projecting garment-supporting lugs having slits therein, a second rectangular portion connected with the first mentioned portion and adapted to be folded so that its upper corners may be inserted into said slits to reinforce said lugs, and a hook-shaped portion formed in said portions. 90 95 100

4. A device as claimed in claim 3, wherein said lugs are arranged to be folded inwardly upon the rectangular portion with which they are connected. 100

5. A garment-hanging device comprising a paper sheet shaped to form a hanger portion having inwardly foldable, garment-supporting lugs, and a cross-shaped packaging portion connected with said hanger portion, a fold line being provided across said packaging portion, and a hook being formed in said hanger portion and adapted to protrude through a slit on said fold line when said packaging portion is folded about said fold line, substantially as described. 105 110 115

In testimony whereof I have affixed my signature.

JOSEPH HIRSCH VINEBERG. 115
